FILLING MACHINE FOR AERATED MINERAL
WATER SIPHON BOTTLES

Leonard Eugene Cowey, Surrey, England

Application September 28, 1934, Serial No. 746,002
In Great Britain September 29, 1933

6 Claims. (Cl. 226—62)

This invention relates to machines for filling siphon bottles and like containers with aerated waters and beverages, and has for its object to simplify and improve the construction of such filling machines and increase the efficiency and safety thereof.

According to this invention, a rotary machine for filling siphon bottles and like containers with aerated liquids under pressure comprises filling and snifting valves that are connected to a plurality of filling heads, each of which is adapted for connection to a siphon bottle or like container so as to maintain the latter in constant communication with the filling and snifting valves, which are common to all the filling heads and are mounted so that they can rotate relatively to a series of controlling cams by which such filling and snifting valves are alternately operated so that the siphon bottles or other containers are progressively filled and snifted as the machine rotates.

The filling valve of the machine controls the supply of aerated liquid under pressure to the several filling heads, and the snifting valve is connected to an adjustable outlet valve or to a suitable counter-pressure chamber, while the filling heads of the machine are arranged in combination with holders that are adapted to receive the heads of inverted siphon bottles and to automatically engage the spouts or nozzles of such siphon heads with the filling heads of the machine so that the siphon bottles or other containers are progressively filled and snifted as the machine rotates.

The invention is more particularly described and ascertained in the following description and appended claims, and illustrated in the accompanying drawings wherein similar references indicate like parts.

Fig. 1 is a fragmental sectional elevation of a rotary filling machine for siphon bottles constructed in accordance with the present invention; Fig. 1a is a vertical section illustrating the lower bearing of the main shaft of the machine, presently referred to; Fig. 2 is a sectional plan view on the line 2—2 Fig. 1; Fig. 3 is a sectional elevation on an enlarged scale illustrating the filling and snifting valves and parts associated therewith; Fig. 4 is a detail sectional plan view on the line 4—4 Fig. 1 and drawn to an enlarged scale further illustrating the cams for controlling the filling and snifting valves and the connections of the latter.

Fig. 5 is a vertical sectional view of one of the filling heads of the machine and the siphon bottle

holder associated therewith showing the position of such parts when a siphon bottle is held in operative engagement with the filling head; Fig. 6 is a similar detail view showing the relative positions of the filling head and its associated siphon bottle holder when the bottle is released from engagement with the filling head; Fig. 7 is a plan view drawn to an enlarged scale further illustrating the construction of one of the siphon bottle holders; Fig. 8 is a detail view in plan on the line 8—8 Fig. 1 illustrating the driving gear by which the machine is operated; Fig. 9 is a detail view in section illustrating the arrangement of the pulleys 95 and 96 and the slip clutch, and Fig. 10 a detail sectional view illustrating one application of a counter-pressure chamber to the machine. As shown, the machine frame comprises a table 1 centrally perforated at 2 and secured by bolts and nuts 3 to brackets 4 mounted on vertical pillars 5, which pillars are secured together at the bottom by angle irons ties 6, and at the top by an annular plate 7, the ties 6 and plates 7 being respectively secured by bolts 6a and 7a to brackets 6b and 7b mounted on the pillars 5.

A vertical shaft 8 is rotatably mounted on ball bearings 9 on the table 1 and carries at its upper end a tubular extension 10 furnished with diametrically opposed tubular radial arms 11 and 12 in which are mounted the filling and snifting valves of the machine, while the lower end of the shaft 8 passes through the central aperture 2 of the table 1 and is connected to the driving gear of the machine as presently described.

The lower end of the tubular extension is sealed by a plug as indicated at 10a, and is furnished with a perforated external flange 10b which is bolted to a counterpart perforated flanged head 8a on the vertical shaft 8 so that the tubular extension rotates with such shaft. The upper end of the extension 10 runs on ball bearings 13 mounted in a tubular socket 18 in a dome-shaped bridge 19 provided with a perforated peripheral flange 19a by which it is bolted to the annular plate 7 of the machine frame in axial alignment with the central aperture 2 of the table 1.

The ball bearings 13 are mounted between races 14 and 15 carried on the extension 10 and in the socket 18 respectively. The race 14 is retained on the tubular extension between flanged collars 14a and 14b mounted upon such extension, while the race 15 is retained in the socket 18 between a packing 15a in the lower end of the socket and a sleeve 16 that is secured in the

upper part of the socket by a centrally perforated plate 17 that forms a cover for the socket 18 of the bridge piece and fits flush in a recess 17a in the upper surface of such bridge piece as shown at Fig. 3.

The upper end of the tubular extension 10 passes through the perforated cover plate 17 on the bridge piece and is provided with a gland 20 and a hat leather 21 so as to make a fluid tight 10 running joint with a tubular coupling 22 adapted for connection to a supply of aerated liquid under pressure. The coupling 22 is retained in position by a perforated locking plate 23 detachably secured by screws 23a to a perforated guide plate 15 24 carried by bolts 25 secured to the bridge piece 19.

The radial arm 11 of the tubular extension 10 forms a housing for the filling valve 26 and for the snifting valve 27, each of which valves is 20 mounted upon the end of a corresponding spindle. The filling valve 26 controls an inlet port 11a by which the radial arm 11 is connected with the bore of the tubular extension 10; such inlet valve is mounted on the reduced end 28a of a 25 spindle 28 that is slidably mounted in the opposite site radial arm 12 and works fluid tight through a packing 29 and a gland 30 screwed in the outer end of the radial arm 12. The snifting valve 27 is mounted on the reduced end 27a of a spindle 27b so as to control the inlet port 30a of a 30 gas chamber 30b which is secured in the outer end of the radial arm 11 by a coupling nut 31 so that such gas chamber forms an extension of the radial arm 11. The gas chamber 30b is furnished with an outlet port 30c (see Figs. 3 and 4) 35 and is provided with a packing 32 and a gland 33 through which the end of the snifting valve spindle works fluid tight.

The filling valve 26 and the snifting valve 27 40 are both controlled by the coil spring 26a by which such valves are normally held closed.

The glands 30 and 33 of the filling and snifting valves each terminates in a socket 35 furnished with a recessed slideable plunger 36 that carries 45 a cross pin 37 which respectively carry anti-friction rollers 38 and 38a. The anti-friction rollers project through lateral slots 38b in their corresponding sockets and are each carried on the corresponding cross pin 37 together with a distance piece 39, arranged so that the anti-friction rollers 38 and 38a are respectively brought into 50 operative engagement with two superimposed sets of cams 40 and 41 which are bolted to the annular plate 7 of the machine frame, as shown in 55 Figs. 1, 3 and 4.

The anti-friction roller 38 is arranged to engage the upper series of cams 40 through which is controlled the operation of the filling valve 26, while the anti-friction roller 38a is arranged 60 on its cross pin 37 so as to operably engage the lower series of cams 41 through which is controlled the snifting valve 27.

The radial arm 11 is furnished with two laterally disposed outlet ports 11b that are connected through pipes 42 to opposite sides of an annular header 43 by which the filling and snifting valves are connected to the several filling heads of the machine.

The annular header 43 is arranged in a carrier frame consisting of centrally perforated upper and lower plates 44 and 45 which are mounted upon upper and lower flanged collars 44a and 45a secured to the vertical shaft 6, see Fig. 1, 75 and are connected by vertical rods 46 furnished

with sleeves or distance pieces 46a that form supports for the annular header 43.

As indicated at Fig. 5 the annular header is of an angular cross section and comprises inclined external bosses 43a and an internal horizontal flange 43b and has an internal annular channel 47 formed therein, which channel is furnished with a series of outlet passages 47a, each of which leads to a corresponding filling head as presently described.

The header is furnished with an annular closure 48 furnished with an internal flange 48a and with an annular packing 49 which is adapted to seat on the channelled annular surface of the header 43.

The vertical rods 46 pass through perforations in the internal flanges 43a and 48a of the annular header 43 and its closure 48 respectively, so that such elements are supported by the sleeves or distance pieces 46a mounted upon such rods, 20 as indicated at Figs. 1 and 5, while the annular closure 48 is secured fluid tight to the annular header 43 by bolts and nuts 50, as indicated at Figs. 1 and 2.

The annular header 43 carries the several filling heads of the machine that are all connected through such header to the filling and snifting valves. The filling heads are mounted in the perforations in the external bosses 43a of the annular header so that such filling heads are 30 interconnected with the annular channel 47 of the header by the passages 47a.

Each filling head is carried by a cylindrical support 51 secured fluid tight in an external boss 43a of the header by a nut 52 as shown at Fig. 5. 35 Each cylindrical support 51 comprises a tubular bore 51a, its lower end terminating in a solid extension 53 of reduced external diameter, while the bore is closed at each end and furnished with laterally disposed ports 54 and 55.

The port 54 is connected with the corresponding passage 47a in the annular header while the port 55 communicates with the cylindrical filling head 56 mounted upon the support 51.

The cylindrical filling head is furnished at its 45 inner end with a perforated cap 57 furnished with a sleeve 58 and a hat leather or other suitable packing 59 by means of which the filling head is slidably mounted together with a controlling spring 60 externally of the cylindrical support 50 51 between the boss 43a of the header and nuts 60a screwed on to the externally threaded sleeve 58.

The reduced solid extension 53 of the support 51 passes through a central perforation in the 55 lower end 56a of the filling head which latter is furnished with an extension 61 in which is mounted the nozzle piece 62 of the filling head. The reduced extension 53 of the cylindrical support is provided with external channels or grooves 60 53a and has a flanged head 53b secured thereon, against which the adjacent end of the slidably mounted filling head 56 is normally held by its controlling spring 60 so that such flanged head forms an abutment that co-operates with an annular seating piece 63 on the adjacent end of the filling head to form a valve which controls the supply of liquid through the outlet nozzle 62 of the filling head.

The outlet nozzle 62 is formed with an internally flared mouth that is furnished with a perforated packing 64 which forms a seat for the spout or nozzle of the head of a siphon bottle or the like, as presently described.

The supports for the siphon bottle to be filled 75

each comprises a pair of frames 65 and 66 which are pivotally mounted on supports 67 secured to the underside of the lower plate 45 of the carrier frame as shown at Figs. 1 and 5 so as to 5 co-operate through rollers 68 and 69 with fixed cam tracks 70 and 71 mounted upon the supports 70x and 71x carried by the table 1 of the machine.

The frames 65 and 66 are pivotally mounted one within the other upon a cross bar 72 secured at 10 each end in the supports 67 as indicated at Fig. 7. The inner frame 65 is furnished at its outer end with a socket 73 that is lined with rubber or other suitable packing 74 and adapted to receive the head 75 of an inverted siphon bottle 76 as indicated at Figs. 5 and 6, such socket being slotted 15 on opposite sides at 73a and 73b to accommodate the spout or nozzle 75a and also the valve lever 75b of the siphon head. The inner frame 65 is also furnished with two rollers 68 and 69 mounted 20 at different levels one behind the other along the longitudinal axis of the frame as indicated at Figs. 5 and 7.

The front roller 68 journals upon a horizontal spindle 68a secured in and at right angles to a 25 cross bar 68b of the inner frame so that the roller 68 can run upon the fixed cam track 70 mounted upon the table of the machine.

The rear roller 69 is journalled upon the lower end of a vertically disposed spindle 69a mounted 30 in a sleeve 69b that is carried by a horizontally disposed sleeve 69c pivotally mounted upon the cross bar 72 which carries the frames and controlled by springs 76 connected to the outer frame 66. The rear roller 69 is thus disposed at right 35 angles to the front roller 68 and at a lower level so that it is held in engagement with the face of the second cam track 71 as indicated at Fig. 5.

The pivotally mounted horizontal sleeve 69c is furnished with an annular tail piece 69d which 40 is adapted to engage with the cross bar 66a of the outer frame 66, which crossbar is furnished with extensions 66b which carry the rear cross-bar 66d to which are attached the ends of the springs 76.

The outer frame 66 is dimensioned so as to project beyond the front of the inner frame 65, the projecting front of the outer frame being furnished with a crossbar 77 that carries a loosely mounted roller 78 arranged so as to register with 45 the vertical slot 73b in the adjacent face of the socket 73 mounted on the inner frame.

The outer cam track 70 is formed with a drop section 70a connected at each end by inwardly inclined sections 70b (see Fig. 1), while the cam 50 track 71 is formed with a raised section 71a connected at each end by inwardly inclined sections 71b to the main body of the cam track 71.

The cam track 71 has a smaller radius than the cam track 70 and is disposed at a lower level, 55 while the two cam tracks are generally concentric except at their dropped and raised sections which are arranged at the receiving and delivery side of the machine; thus, as the rollers 68 and 69 follow the contours of the cam tracks 70 and 71, they 60 allow the pivoted frames of the siphon holders to drop into the position indicated at Fig. 6 as the holder frames successively rotate past the delivery and receiving side of the machine so that the receiving socket 73 is outwardly inclined.

The siphon bottle to be filled is inverted and its head placed in the outwardly inclined socket 73 so that the spout 75a thereof projects through the slot 73a of the socket adjacent to the nozzle 75 62 of the corresponding filling head 56, while the

lever 75b of the siphon head projects through the slot 73b of the socket.

As the machine continues to rotate the inner frame 65 is raised by the outer cam track 70, thus bringing the socket 73 together with the inverted siphon bottle 76 into the vertical position shown at Fig. 5 and engaging the spout 75a with the nozzle piece 62 of the filling head; this operation forces back the filling head against the resistance of its spring 60, so unseating the flanged head 53b 10 in the nozzle piece so that the latter is connected through the perforated end 56a of the filling head with the interior of the latter.

As this operation is completed the reaction of the cam track 71 on the roller 69 raises the outer 15 frame 66 by tensioning the springs 76 at the rear end thereof, and thus engages the roller 78 on the outer end of the frame 66 with the valve lever 75b of the siphon head, thus opening the siphon head valve so that the container is connected 20 through its siphon head and the filling head 56, header 43 and pipes 42 with the filling and snifting valves, the container being maintained in this position by the reaction of the cam tracks until the machine completes one revolution. 25

As the machine rotates, the filling and snifting valves 26 and 27 are alternately operated by their controlling cams 40 and 41 so that each siphon is progressively charged with gas and with liquid, and snifted, a certain amount of liquid being 30 trapped in the lower end of each of the filling heads.

When the snifting valve is operated gas escapes from the siphon and bubbles through the liquid trapped in the filling head from which it escapes 35 via the header 43 and connecting pipes 42 to the snifting valve chamber and escapes past the open snifting valve to the outlet port 30c of the gas chamber 30b via the escape pipe 31a to an adjustable escape valve 80, (see Fig. 3). 40

As shown, the escape valve is mounted on the upper carrier plate 44 and comprises a housing furnished with an inlet chamber 81 that is furnished with an outlet valve 82 controlled by an adjustable spring 83. The inlet chamber is connected to a pressure gauge 84, while the spring 83 is adjusted by means of a screwed rod 85 that works through a packing 86 arranged in the escape valve housing and is provided with a lock nut 87. 50

The tension of the spring 83 can thus be adjusted to allow the gas to escape past the outlet valve 82 at any required pressure, which is indicated by the gauge, the escaping gas passing off through an outlet 88. 55

As each siphon is snifted the gas pressure therein is reduced so that more liquid can pass into the same on each operation of the filling valve 26 until the siphon bottle 76 is completely filled except for a small residual gas bubble, the 60 complete filling of the siphon bottles being rendered possible by the vertical position in which the same are held during the filling and snifting operations.

As each siphon comes round to the delivery side 65 of the machine the contours of the cam tracks allow the carrier frames to fall into the position indicated at Fig. 6 so disengaging the spout of the siphon head from the corresponding filling head, which latter is immediately returned by 70 its controlling spring 60 against the flanged head 53b, so sealing the same, until another siphon is placed in the carrier and re-engaged with such filling head.

The filled siphon is removed from the carrier 75

frame and an empty siphon is substituted therefor as the machine rotates so that the cycle of operations is performed continuously. The rotatable shaft 3 which carries the moving elements on the machine as above described is furnished with a collar 8b by which it is supported on the ball bearings 9, such ball bearings being supported by a perforated plate 9a mounted in the central perforation 2 of the table 1 of the machine, while the bearings are housed in a flanged cover plate 9b mounted on the shaft 3 as indicated at Fig. 1a.

The lower end of the shaft 3 extends below the table 1 of the machine and is furnished with a worm wheel 98 which is secured thereon by a nut 98a screwed on to the lower end of the shaft 3 so as to clamp the wheel 98 against the sleeve 9c mounted upon the lower end of the shaft 3 as indicated.

20 The worm wheel 98 gears with a worm 9f on a shaft 92 as indicated at Fig. 8. Such shaft 92 is mounted in a sleeve 93 secured by straps 94 to the underside of the table 1 of the machine, the outer end of the shaft being furnished with 25 a loose pulley 95 and a driving pulley 96. The driving pulley 96 is connected through a friction clutch to the shaft 92, such driving gear being enclosed in a case B detachably mounted on the underside of the table 1 (see Fig. 1).

30 As illustrated at Fig. 9, the friction clutch comprises fibre washers 96a and 96b mounted on opposite sides of the driving pulley 96 so that the washer 96a bears against a metal disc 97 on the shaft 92 while the fibre washer 96b forms an 35 abutment for a corrugated metal plate 97a on the opposite face of which a second fibre washer 97b is arranged so as to receive the thrust of a metal washer 98 which is secured by a nut 99 which screws on to an externally threaded sleeve 40 92a on the shaft 92.

By this arrangement the driving pulley 96 is frictionally secured to the shaft 92, the grip being regulated by the adjustment of the nut 99 on the shaft; thus, in the event of any obstruction 45 occurring as the machine rotates, the driving pulley will slip relatively to the shaft 92 and thus greatly minimize the risk of accident to the machine.

109 indicates a belt striker which is conveniently mounted on the underside of the table 1 of the machine in guides indicated at 101, and is connected to an operating lever 102 pivotally mounted to the underside of the table 1.

If desired a counter-pressure chamber may be 55 installed in the machine as illustrated at Fig. 10. As shown, such chamber is comprised between two cylinders 103 and 104 disposed concentrically between upper and lower centrally perforated plates 105 and 106 so as to form an annular counter-pressure chamber 107 about a central bore 108.

The central aperture of the upper plate 105 is of less diameter than that of the inner cylinder 103 so that the inner periphery of the upper plate forms an internal flange 108a at the upper end of the central bore 108.

The counter-pressure chamber so formed is mounted upon the upper end of the rotatable vertical shaft 3 which passes through the central bore 108 by clamping the flange 108a of the top plate 105 between the flanged head 9a of the shaft 3 and the flange 10b of the tubular extension 10, which elements are perforated for the passage of securing bolts 109.

75 In this construction the escape pipe 31a for

the snifted gas released by the operation of the snifting valve 27 is connected to an inlet pipe 31b of the counter pressure chamber instead of directly to an adjustable escape valve as above described with reference to Fig. 3, while the inlet chamber of an adjustable escape valve 80 similar to that illustrated at Fig. 3 is connected to the counter-pressure chamber so as to allow gas to escape from the latter when the internal pressure exceeds a pre-determined limit.

The carrier frame formed by the upper and lower plates 44 and 45 mounted upon the rotatable shaft of the machine may be furnished with radially disposed guards 111 (see Figs. 1 and 2) arranged so that they are interposed between the several siphon bottles placed in the machine, while the machine frame may also be provided with a circular guard, not shown, that is adapted to form a cage between the table 1 and the upper carrier plate 44, such guard being furnished with an opening through which siphon bottles or the like vessels can be removed from and placed in the machine as the latter rotates.

The cams 40 for operating the filling valve 26 have a considerably larger stroke than the cams 41 which operate the snifting valve, such cams being mounted on the machine frame so that when one of the cams 40 for controlling the filling valve is engaged by the friction roller 38, the friction roller 38a on the snifting valve spindle 30 is free, and vice-versa, as indicated at Fig. 4.

The cams 40 and 41 may be interchanged for other cams according to the capacity of the siphon bottles to be filled with aerated liquid.

Thus, in the case of bottles or the like of large 35 capacity, longer cams 40 for controlling the filling valve 26 may be employed so as to hold such valve open for a longer period, and thus increase the volume of liquid admitted at each operation 40 of the filling valve.

It will be understood that the features of construction and arrangement of the machine may be considerably varied and modified without departing from the nature of the invention hereinbefore described and illustrated by way of 45 example.

I claim:—

1. In a rotary machine for filling siphon bottles with aerated liquids, a rotatable structure, a filling valve and a snifting valve unit carried by said structure, a plurality of filling heads with which said unit communicates in common, cams for operating said valves as said structure rotates, holders for siphon bottles arranged in cooperative relation to said filling heads, means for operating said holders so as to engage the containers carried therein with the corresponding filling heads thereby maintaining the bottles in constant communication with said filling and snifting valve unit during each revolution of the machine.

2. In a rotary machine for filling siphon bottles, a frame, a centrally perforated table carried by said frame, a vertical shaft rotatably mounted in said table, a tubular extension connected to said shaft and having radial arms, filling and snifting valves located in the arms of said extension, said valves having spindles projecting through the ends of said arms, a spring cooperating to close said valves, a series of cams for each spindle, said cams being mounted on said frame, said spindles cooperating with alternate cams, a header on said shaft, connections between said filling and snifting valves and said header, a plurality of spring controlled valved filling heads, connec- 75

tions between said heads and said header, a plurality of holders corresponding to said filling heads, supports on said shaft, means pivotally mounting said holders on said supports, each of said holders including a slotted socket for carrying a head of an inverted siphon bottle, rollers for each pivotally mounted holder, a cam track on said table cooperating with said rollers for raising the holders and operatively engaging the heads of the siphon bottles with the spring controlled filler heads so as to maintain the bottles in constant communication with the filling and snifiting valves through the header and the filling heads connected with the header.

15 3. In a rotary machine for filling siphon bottles, a plurality of filling head units, a single filling valve and snifiting valve unit common to all filling head units; said filling head units each comprising a relatively fixed support, a filling head slidably mounted on said support, said support and said head having cooperating valve elements constituting a shut-off, a spring operating on said head and said support to keep said valve elements in the shut-off position; a plurality of siphon 20 bottle holders pivotally mounted on the machine, one for each filling head unit to cooperate therewith and means to pivot said holders to effect an engagement between the siphon bottles' heads and said filling heads, and to effect movement of said filling heads to open the shut-off 25 valve elements thereof.

4. In a siphon bottle filling machine, a filling valve and a snifiting valve unit, a plurality of filling heads cooperating with said unit, cams for actuating the filling and snifiting valves of said unit, a plurality of holders for carrying siphon bottles, there being one holder for each filling head, said holders each comprising a bottle-head receiving socket, two frames pivotally mounted one inside the other, the inner frame carrying said socket, two rollers carried by the inner frame one being fixedly mounted thereon and the other pivotally and yieldably mounted thereon, cam tracks with which said rollers engage for raising and lowering said frames during the rotation of the machine, said outer frame being constructed slidably to engage the valve 30

lever of the siphon head mounted in the adjacent socket so as to open the siphon valve during the rotation of the machine.

5. In a rotary machine for filling siphon bottles, a plurality of filling head units interconnected with each other through a header, a single filling valve and snifiting valve unit connected through said header to all the filling head units, said filling head units each comprising a relatively fixed support, a filling head slidably 10 mounted on said support, said support and said head having cooperating valve elements constituting a shut-off, a spring operating on said head and said support to keep said valve elements in the shut-off position; a plurality of 15 siphon bottle holders pivotally mounted on the machine, one for each filling head unit to cooperate therewith, and means to pivot said holders to effect an engagement between the siphon bottles' heads and said filling heads, and to effect move- 20 ment of said filling heads to open the shut-off valve elements thereof.

6. In a rotary machine for filling siphon bottles, a filling valve and a snifiting valve unit, a plurality of filling heads cooperating through a 25 header with said unit, a plurality of holders for carrying siphon bottles, there being one holder for each filling head, said holders each comprising a bottle-head receiving socket, two frames pivotally mounted one inside the other, the inner frame 30 carrying said socket, two rollers carried by the inner frame, one being fixedly mounted thereon, and the other pivotally and yieldably mounted thereon, cam tracks with which said rollers engage, for raising such frames so as to engage the 35 inverted bottles' heads with the corresponding filling heads and hold the bottles upright, said cam tracks cooperating in said frames, so as to lower the latter and cant the bottles outwards from the machine as the heads of the latter are 40 successively released from the filling heads, said outer frame being adapted to engage the valve lever of the siphon head mounted in the adjacent socket so as to open the siphon valve when the frames are raised by said cam tracks. 45

LEONARD EUGENE COWEY.
